DESIGN FOR AN AUTOMOBILE DOOR OR SIMILAR ARTICLE

Peter J. Swofford, Fort Worth, Tex.

Application December 31, 1940, Serial No. 97,754

Term of patent 7 years

To all whom it may concern:

Be it known that I, Peter J. Swofford, a citizen of the United States, residing in Fort Worth, in the county of Tarrant and State of Texas, have invented a new, original, and ornamental Design for an Automobile Door or Similar Article, of which the following is a specification, reference being had to the accompanying drawing, forming part thereof, in which:

automobile door or similar article, showing my new design;

Figure 2 is an inside perspective view thereof; and

I claim:

The ornamental design for an automobile door or similar article, as shown.

PETER J. SWOFFORD.
